CLAIM

The ornamental design for a mobile computer housing, as shown and described.

DESCRIPTION

FIG. 1 is a front perspective view of a first embodiment of the mobile computer housing.

FIG. 2 is a front elevation view of the first embodiment of the mobile computer housing.

FIG. 3 is a rear elevation view of the first embodiment of the mobile computer housing.

FIG. 4 is a top plan view of the first embodiment of the mobile computer housing.

FIG. 5 is a bottom plan view of the first embodiment of the mobile computer housing.

FIG. 6 is a right side elevation view of the first embodiment of the mobile computer housing.

FIG. 7 is a left side elevation view of the first embodiment of the mobile computer housing.

FIG. 8 is a front perspective view of a second embodiment of the mobile computer housing.

FIG. 9 is a front elevation view of the second embodiment of the mobile computer housing.

FIG. 10 is a rear elevation view of the second embodiment of the mobile computer housing.

FIG. 11 is a top plan view of the second embodiment of the mobile computer housing.

FIG. 12 is a bottom plan view of the second embodiment of the mobile computer housing.

FIG. 13 is a right side elevation view of the second embodiment of the mobile computer housing; and,

FIG. 14 is a left side elevation view of the second embodiment of the mobile computer housing.

Broken lines and unshaded portions contained within broken lines depict parts of the mobile computer housing that form no part of the claimed design.
